UNITED STATES PATENT OFFICE.

GEORGE C. THOMAS, OF MALDEN, MASSACHUSETTS, ASSIGNOR TO CONVERSE RUBBER SHOE CO., A CORPORATION OF MASSACHUSETTS.

ARCTIC OR GAITER.

Application filed May 10, 1924. Serial No. 712,346.

This invention pertains to artics or gaiters preferably composed of waterproofed or rubberized cloth for wear in snowy or rainy weather.

5 My arctic or gaiter is adapted to be worn over the regular foot covering and is so constructed as to give the maximum protection to the wearer during wet and snowy weather. I also obviate the cumbersome 10 closures as now used on such articles and have devised a novel closure which is superior in operation, and which gives a much neater appearance, as the closure means are completely hidden from view.

15 The gaiter comprises a central bellows-like tongue, side flaps which fold over the tongue, and a cuff around the top of the gaiter. The cuff, in one form of the invention, is turned down from the top of the 20 gaiter, and is not intended to be turned up; in another form, the cuff, while normally turned down, may also be turned up and fastened in the upturned position.

25 Adjustable fastening means are provided with both forms whereby a snug fit is had for ankles of various sizes.

In the attached drawings,

Fig. 1 is a perspective view of my gaiter in an open position ready for insertion of 30 the wearer's foot.

Fig. 2 is a perspective view showing my gaiter in closed position, as worn.

35 Fig. 3 is a side view, with a portion of the cuff turned back to illustrate the closure means.

Fig. 4 is a modified form of my gaiter, being a perspective view thereof.

40 Fig. 5 is a perspective view of the modification, showing the closure flaps in opened position.

Fig. 6 is a perspective view of the modified form having the cuff portion in a down-turned position.

45 Fig. 7 is a perspective of the cuff in up-turned, closed position.

More specifically in the drawings, illustrating an embodiment of my invention, 1 denotes the foot portion of my gaiter, which 50 may be composed of rubber or other waterproof material; 2 and 3, the upper foot and leg portions respectively, preferably composed of rubberized cloth or the like.

The leg portion 3 includes side flaps F, which are adapted to overlap each other, 55 and to overlap a tongue 4, preferably a

bellows tongue. The lower portion 4^a of the tongue covers the instep of the foot of the wearer and merges into the foot portion 2, being preferably integral therewith. The tongue 4 has its sides cut away 60 as indicated at 5—5, the sides being attached to the side flaps F along the lines, 15—15. By so attaching the side portions 5—5 of the tongue 4 along the lines 15—15 it will be readily seen that it is impossible 65 for snow or rain to creep into the gaiter through the closure. The tongue 4 is made wide enough to allow the side flaps F to spread apart so that the gaiter may be readily slipped on or off. Fig. 1 shows the 70 gaiter in open position with the side flaps thrown back. When the flaps are closed, the sides of the tongue fold along the line 17, and so do not wrinkle or create a bulge 75 on the outside of the gaiter.

The flaps F are of substantially the same shape; the cuff 6 is formed as an upward extension of the side flaps and is substantially coextensive therewith. The side flaps 80 preferably overlap slightly, such overlapping being on a median line; the flaps are shaped so that they overlap only below their upper edges, and the adjacent vertical edges of the cuffs are symmetrically positioned a little to either side of the median line, giving 85 a pleasing symmetrical effect, as shown in Fig. 2.

The cuff 6 is preferably integral with the leg portion 3, is attached to the upper edge 90 of the leg portion, and is adapted to normally fold over, and lie against the leg portion when in downturned position.

One of the flaps F is extended, as at 7, to form a fastening strap 7. Slidably mounted on the strap 7, for adjustable 95 movement, is the fastener 8, which is adapted to engage with the stud 9 when the side flaps F are brought together. After the flaps F are folded over the tongue 4, the snap fastener 8 is snapped onto the stud 9, 100 thus retaining the gaiter in closed position, which insures a snug waterproof closure for the gaiter. The closure is adjustable, so that it may be used for different sized ankles. The fastening elements 8 and 9 105 merely illustrate one convenient form of adjustable fastening; evidently other forms could be used.

It will be observed in Figs. 2 and 3 illustrating the preferred construction that in 110

closed position the strap 7, together with the snap fastener 8 and stud 9 are completely concealed from view beneath the cuff 6, giving the gaiter a neat and finished appearance. The fastening means could be placed below the cuff, if desired.

Figs. 1 to 3 inclusive, illustrate the preferred form of my gaiter, while Figs. 4 to 7 inclusive, illustrate a modified form 10 thereof.

In the modified form, the cuff 6 is adapted to be retained in either upturned or downturned position. The object of this arrangement, is to provide protection for 15 the wearer in deep snow, that is, where the height of the snow is above the height of the cuff 6 in downturned position. When deep snow is encountered, the cuff 6 may be turned up and fastened snugly around the 20 wearer's leg, affording additional protection.

In the modified form, the construction is generally similar to the form shown in Fig. 1. The modification relates particularly to the fastening means of the cuff.

A fastening strap 20 is anchored to the underside of the cuff 6 by suitable means, such as the ball and socket fastening elements 21, one part of the fastening being on 30 the strap and the other on the underside of the cuff. The strap may be swung about 21 as a pivot. Slidably mounted on the other end of the strap 20 is a fastening element 22 which may be provided with a 35 socket 22' for engaging with the ball fastener 23 on the underside of the other end of the cuff 6.

The side flaps F are adjustably fastened together as in Figs. 1-3.

40 With the modified form, three different positions are possible: First, the cuff may be turned down, and the fastening strap 20 held in the inoperative position, as in Fig. 4. This is practically the same as in Fig. 2. 45 Second, with the cuff still turned down, the strap 20 may be swung about its anchorage 21 as a pivot, as indicated in dotted lines in Fig. 5, and secured to the fastener 23, as illustrated in Fig. 6; this pulls the edges 50 of the cuffs closer together, and gives a snug and neat fit about the ankle by imposing a circumferential restricting force around the upper part of the ankle, underneath the cuff. There are thus provided two distinct 55 adjustments for fit, one by the adjustable securing means for the side flaps, and the other by the adjustable securing means for the strap 20 underneath the cuff, the latter especially serving to give a snug and tight 60 fit around the upper edge of the arctic. And third, the cuff may be turned up as in Fig. 7 and the strap 20 swung about its anchorage and secured to the fastener 23; this last position is particularly for deep 65 snow.

While I have illustrated my invention in some detail, it should be understood that the invention is not to be limited to such details, but may be carried out in other ways, as expressed within the scope of the following 70 claims.

I claim as my invention:—

1. In a gaiter, the combination with a foot portion, of an instep covering portion extended upwardly to form a bellows tongue, 75 side flaps to which the bellows tongue is attached, foldable over the bellows tongue, a cuff turned downwardly from the upper edges of the side flaps, securing means, carried by one of the flaps and detachably secured to the other flap, for holding the side flaps folded over each other and over the bellows tongue, and a second securing means positioned underneath the cuff for imposing a circumferential restricting force 80 around the upper part of the gaiter, underneath the cuff.

2. In a gaiter, the combination with a foot portion, of side flaps foldable into overlapping relation, an instep covering portion, a downwardly turned cuff at the upper edge of the side flaps, the instep covering portion being extended upwardly to form a bellows tongue the edges of which are attached to the side flaps, a securing device carried by 90 one of the flaps and detachably secured to the other flap, said securing device being positioned underneath said downturned cuff, for holding the side flaps folded over the bellows tongue, in overlapping relation with each other, and a second securing means, positioned underneath the cuff, for imposing a circumferential restricting force around the upper part of the gaiter, underneath the cuff. 95

100 3. In a gaiter, the combination with a foot portion, of an instep covering portion extended upwardly to form a bellows tongue, side flaps to which the bellows tongue is attached, foldable over the bellows tongue, a cuff turned downwardly from the upper edges of the side flaps, securing means, carried by one of the flaps and detachably secured to the other flap, for holding the side flaps folded over each other and over the bellows tongue, and means, carried by one end of the cuff and detachably engageable with the other end of the cuff, for holding the cuff turned upwardly around the leg of the wearer. 115

120 4. In a gaiter, the combination with a foot portion, of side flaps foldable into overlapping relation, an instep covering portion, a downwardly turned cuff at the upper edge of the side flaps, the instep covering portion being extended upwardly to form a bellows tongue the edges of which are attached to the side flaps, a securing device carried by one of the flaps and detachably secured to the other flap, said securing de- 125 130

vice being positioned underneath said down-turned cuff, for holding the side flaps folded over the bellows tongue, in overlapping relation with each other, and means, engageable with the ends of the cuff and normally concealed thereby when the cuff is in down-turned position, for holding the cuff in up-turned position around the leg of the wearer.

5. In a gaiter, the combination with a foot portion, of an instep covering portion extended upwardly to form a bellows tongue,

10

side flaps to which the bellows tongue is attached, a cuff formed as an upward extension of the side flaps and foldable downwardly over the flaps, the two flaps being of 15 substantially the same shape and only overlapping at a point well below the upper edges thereof, and means for detachably securing the two flaps together.

In testimony whereof I affix my signature.

GEORGE C. THOMAS.
